UNITED STATES PATENT OFFICE

100,845

DESIGN FOR A MECHANICAL LEAD PENCIL OR ARTICLE OF SIMILAR NATURE

Parker Z. Bloser, Columbus, Ohio

Application May 13, 1936, Serial No. 62,617

Term of patent 14 years

To all whom it may concern:

Be it known that I, Parker Z. Bloser, a citizen of the United States of America, residing at Columbus, in the county of Franklin, and State of Ohio, have invented a new, original, and ornamental design for a Mechanical Lead Pencil or Article of Similar Nature, of which the following is the specification, reference being had to the accompanying drawing, forming a part hereof:

The figure is a side elevational view of a mechanical lead pencil, showing my new design.

I claim:

The ornamental design for a mechanical lead pencil or article of similar nature, as shown.

PARKER Z. BLOSER.
